(57) **CLAIM**

The ornamental design for the warning light and flange, as shown and described.

DESCRIPTION

FIG. 1 is a front perspective view of a warning light in combination with one embodiment of a flange showing my new design;

FIG. 2 is a front view of the warning light and flange of FIG. 1;

FIG. 3 is a rear view, partially illustrated in broken lines, of the warning light and flange of FIG. 1;

FIG. 4 is a top plan view of the warning light and flange of FIG. 1;

FIG. 5 is a bottom plan view of the warning light and flange of FIG. 1; and,

FIG. 6 is a left side view of the warning light assembly, the opposite right side view being a mirror image thereof.

No claim is made to the portions shown in broken lines.
